ABSTRACT

A cord management device securable to objects lacking a cord management system. An embodiment includes a flexible substratum on which two outwardly facing hooks are secured in a longitudinally spaced manner. An embodiment further includes a receptacle adapted to receiving and temporarily house the prongs on an electrical cord. The flexible substratum preferably includes an adhesive, magnet, or fastener to temporarily or permanently secure the device to objects. The device is thereby attachable to an object to aid in the securement of an electrical cord.

CORD MANAGEMENT DEVICE

CROSS-REFERENCE TO RELATED APPLICATIONS

This nonprovisional application is a continuation of and claims priority to nonprovisional application Ser. No. 15/664,426, entitled "CORD MANAGEMENT DEVICE," filed Jul. 31, 2017 by the same inventor, which claims priority to nonprovisional application Ser. No. 15/464,414, now U.S. Pat. No. 9,755,354, entitled "CORD MANAGEMENT DEVICE," filed Mar. 21, 2017 by the same inventor.

BACKGROUND OF THE INVENTION

1. Field of the Invention

This invention relates, generally, to the management of cords. More specifically, it relates to the management of electrical cords connected to devices not equipped with a means for organizing and storing the electrical cords connected to said devices.

2. Brief Description of the Prior Art

There are many electronic devices that require electrical cords and yet fail to include a means for organizing and storing their respective electrical cords when the devices are not in use. These cords can become tangled or are left in a messy heap, which can be a tripping hazard. Some attempt to wrap the electrical cord around the object itself, but the cord rarely remains securely wrapped.

Accordingly, what is needed is a versatile cord management device that can be attached to nearly any object and provides a structure for securely restraining an electrical cord and the cord's plug. However, in view of the art considered as a whole at the time the present invention was made, it was not obvious to those of ordinary skill in the field of this invention how the shortcomings of the prior art could be overcome.

All referenced publications are incorporated herein by reference in their entirety. Furthermore, where a definition or use of a term in a reference, which is incorporated by reference herein, is inconsistent or contrary to the definition of that term provided herein, the definition of that term provided herein applies and the definition of that term in the reference does not apply.

While certain aspects of conventional technologies have been discussed to facilitate disclosure of the invention, Applicant in no way disclaims these technical aspects, and it is contemplated that the claimed invention may encompass one or more of the conventional technical aspects discussed herein.

The present invention may address one or more of the problems and deficiencies of the prior art discussed above. However, it is contemplated that the invention may prove useful in addressing other problems and deficiencies in a number of technical areas. Therefore, the claimed invention should not necessarily be construed as limited to addressing any of the particular problems or deficiencies discussed herein.

In this specification, where a document, act or item of knowledge is referred to or discussed, this reference or discussion is not an admission that the document, act or item of knowledge or any combination thereof was at the priority date, publicly available, known to the public, part of common general knowledge, or otherwise constitutes prior art

under the applicable statutory provisions; or is known to be relevant to an attempt to solve any problem with which this specification is concerned.

5 BRIEF SUMMARY OF THE INVENTION

The long-standing but heretofore unfulfilled need for an aftermarket cord management device is now met by a new, useful, and nonobvious invention.

10 The novel structure includes a pair of outwardly facing hooks disposed in a longitudinally spaced configuration. The hooks are preferable attached to a top surface of a flexible substratum. The bottom surface of the substratum includes adhesive, magnet(s), or fastener(s), thereby allowing the device to be secured to an object in need of a cord management device.

An embodiment includes a receptacle secured between the pair of outwardly facing hooks. The receptacle has two or more apertures adapted to receive prongs extending from the 20 plug end of an electrical cord. In an embodiment, the receptacle is offset from the midline between the two hooks, such that a surface opposite of the surface containing the two or more apertures is closer to the nearest hook than the 25 surface having the apertures.

An embodiment includes a catch and a receptacle. The catch has a bottom surface with an adhesive, fastener, or magnet for attaching the catch to an object. The receptacle has a side containing two or more apertures adapted to 30 receive prongs extending from a plug end of an electrical cord, and a bottom surface with an adhesive, fastener, or magnet for attaching the receptacle to an object. The catch is preferably secured to an object in an orientation where the catch is facing the side of the receptacle having the two or more apertures.

An embodiment includes a flexible substratum on which the catch and receptacle are secured. The substratum in turn has a bottom surface with an adhesive, fastener, or magnet, thereby allowing the device to be secured to an object in 35 need of a cord management device.

In an embodiment, the receptacle and the catch are manufactured as a single unit and adapted to separate into two components prior to use, using for example a perforated seam.

40 45 These and other important objects, advantages, and features of the invention will become clear as this disclosure proceeds.

The invention accordingly comprises the features of construction, combination of elements, and arrangement of parts that will be exemplified in the disclosure set forth hereinafter and the scope of the invention will be indicated in the claims.

BRIEF DESCRIPTION OF THE DRAWINGS

55 For a fuller understanding of the invention, reference should be made to the following detailed description, taken in connection with the accompanying drawings, in which:

FIG. 1A is a side view of an embodiment of the present invention.

60 FIG. 1B is a top view of an embodiment of the present invention.

FIG. 2 is a perspective view of the present invention secured to a cylindrical object, highlighting the flexibility of the present invention.

65 FIG. 3 is a perspective view of the substratum wrapping around a curved corner of an object to highlight the flexibility of the present invention.

FIG. 4 is a perspective view of an embodiment of the invention with a cord coiled around the longitudinally spaced hooks.

FIG. 5A is a perspective view of the present invention displaying the apertures in the receptacle.

FIG. 5B is a perspective view of the present invention displaying the apertures in the receptacle.

FIG. 6 is a perspective view of an embodiment of the present invention that uses a receptacle without the hooks.

FIG. 7 is a perspective view of an embodiment having a receptacle and a catch.

FIG. 8 is a perspective view of an embodiment having a receptacle and a catch.

FIG. 9 is a perspective view of an embodiment in which the receptacle and catch are sold as a single separable unit.

FIG. 10 is a top view of an embodiment of the present invention having 3 hooks.

DETAILED DESCRIPTION OF THE INVENTION

In the following detailed description of the preferred embodiments, reference is made to the accompanying drawings, which form a part thereof, and within which are shown by way of illustration specific embodiments by which the invention may be practiced. It is to be understood that other embodiments may be utilized, and structural changes may be made without departing from the scope of the invention.

The present invention is a novel apparatus attachable to any device for securing an electrical cord and plug. As depicted in FIGS. 1, an embodiment of the present invention includes substratum 102 having top surface 104 and bottom surface 106. Substratum 102 is preferably flexible to conform to the surface over which the substratum is laid. As depicted in FIGS. 2 and 3, the flexibility of substratum 102 allows the apparatus to easily conform to cylindrical objects and rounded edges.

In an embodiment, substratum 102 is adapted to flex at least 45 degrees between its two ends. Preferably, an embodiment can flex generally between 0 and 360 degrees between its two ends, and in some instances between 25 and 180 degrees. Moreover, an embodiment is adapted to flex in a direction to create a generally concave bottom surface 106.

Bottom surface 106 includes an adhesive, fastener, one or more magnets, or another securing instrument known to a person of ordinary skill in the art (not shown) to ensure that substratum 102 can be secured to an object. Bottom surface 106 may use a fastener that provides temporary or permanent affixation to the object on which substratum 102 is secured. In an embodiment, substratum 102 is attachable without tools. In other words, the fastener on bottom surface 106 is a tool-less fastener.

Top surface 104 includes first hook member 108 proximate to a first end of substratum 102 and second hook member 110 proximate to a second end of substratum 102. Hooks 108, 110 are preferably curved or angular structural members directed away from each other. In an embodiment, first hook member 108 and second hook member 110 are arranged in opposing configuration such that the hooks are convexly oriented from the perspective of the midpoint of the substratum. Hooks 108, 110 in combination provide a structure about which cord 112 can be coiled as depicted in FIG. 4.

In an embodiment, top surface 104 of substratum 102 also includes receptacle 114. Receptacle 114 may be temporarily or permanently affixed to top surface 104 of substratum 102.

Referring to FIGS. 5, receptacle 114 includes apertures 116 configured to receive the prongs extending from the plug end of electrical cord 112. As depicted in FIG. 5A, an embodiment of receptacle 114 includes two slot-shaped apertures 116 to receive a two-prong electrical plug. Alternatively, FIG. 5B provides an embodiment of receptacle 114 having three apertures 116 to receive a three-prong electrical plug. The current figures depict receptacle 114 having various apertures 116 consistent with the most common electrical plugs found in the United States. It is considered, however, that an embodiment of receptacle 114 may have different aperture designs for receiving any configuration of prongs extending from any type of electrical plug.

Receptacle 114 is preferably located between hooks 108, 110, but it is considered that receptacle 114 may be located outside of the two hooks. In addition, surface 114a of receptacle 114 having apertures 116 preferably faces one of the hooks 108, 110 to ensure that the cord's plug aligns generally with coiled cord 112, as depicted in FIG. 4.

In an embodiment, receptacle 114 is offset from the midpoint line between hooks 108, 110 such that surface 114b, the surface opposite of 114a, is closer to the nearest hook than surface 114a. This is best illustrated in FIGS. 1, wherein surface 114b is closer to hook 108 than surface 114a. As a result, ample room is provided to accommodate the plug end of cord 112, which is typically a more rigid section of the cord.

In an embodiment, surface 114b may be the surface of the receptacle that is oppositely disposed from substratum 102 to account for "low profile" plugs, i.e., prongs that are perpendicular to the longitudinal axis of the plug end of the electrical cord. In addition, surface 114b may be any surface except for the object-facing surface, i.e., the surface mated to substratum 102 or simply the surface having the ability to attach to an object.

Referring now to FIG. 6, an embodiment of the present invention includes receptacle 114 without hooks 108, 110. Receptacle 114 may rest atop a substratum or simply rely on a bottom surface 114d having an adhesive, fastener, one or more magnets, or another securing instrument known to a person of ordinary skill in the art (collectively denoted by reference numeral 118) to ensure that receptacle 114 can be secured to an object. The method of securing receptacle 114 may be temporary or permanent.

Referring now to FIG. 7, an embodiment includes receptacle 114 with catch 109. In an embodiment, both receptacle 114 and catch 109 are secured to top surface 104 of a single substratum 102 or each is secured to their own independent substratum 102. Alternatively, receptacle 114 and catch 109 may be used without a substratum and include their own respective securing instrument for attaching to a particular object.

Referring now to FIG. 8, regardless of whether a receptacle 114 and catch 109 are used with substratum 102, catch 109 preferably faces surface 114a. As a result, cord 112 can be wrapped around an object between catch 109 and receptacle 114, and the plug end can mate with receptacle 114 while catch 109 prevents cord 112 from sliding off of the object around which cord 112 is wrapped. Preferably, catch 109 is secured to an object proximate to the point at which cord 112 attaches to the object because electrical cords tend to loosen and slide from the end at which they attach to an object.

Alternatively, receptacle 114 can be secured to the object such that the longitudinal axis (axis extending between surface 114a and 114b) of receptacle 114 is misaligned with the longitudinal axis of catch 109. For example, receptacle

114 may be perpendicularly oriented with respect to catch 109 such that receptacle 114 shown in FIG. 8 would rotate 90-degrees in a clockwise direction prior to being secured to the object. As a result, the plug end of cord 112 would be parallel with the section of cord secured with catch 109 when the plug end mates with receptacle 114.

Referring now to FIG. 9, an embodiment includes receptacle 114 and catch 109 being manufactured and sold as a single unit to reduce costs. The unit preferably includes a perforated seam to allow the two objects to easily separate and be positioned as desired.

It should be noted that catch 109 and hooks 108, 110 may have the same shape and thus capable of performing the same function.

As shown in FIG. 10, some embodiments further include three or more hooks (108, 110, and 111) equidistantly spaced in a non-linear fashion.

In an embodiment, receptacle 114 is adapted to receive a portion of cord 112 rather than the prongs extending from the plug end of cord 112. Instead of having prong apertures 116, the alternative receptacle design has a cord receiving area adapted to receive and temporarily secure a cord. The alternative receptacle may have any shape and design known to a person of ordinary skill in the art such that the alternative receptacle is capable of temporarily securing a cord.

In addition, it should be noted that the optimal use of the device includes the following sequential steps for identifying an attachment location: (1) identifying a preliminary attachment location for the device, (2) securing the cord with the device, (3) adjusting the location of the device to ensure that the cord remains taught when secured, and (4) attaching the device at the adjusted location. These steps will ensure that the cord can be consistently secured to the device in an optimal location on the object that was lacking a cord management device.

Glossary of Claim Terms

Cord: is a flexible elongated object, typically containing an electrical conduit.

Hook: is an angular or curved object for holding or suspending something.

Outwardly Facing: is an orientation in which the curved or obtusely angled portion of the hooks face away from each other.

Inwardly Facing: is an orientation in which the curved or obtusely angled portion of a hook face towards an object.

Non-Functional Receptacle: is a receptacle that does not transfer electricity from an electrical cord to another object.

The advantages set forth above, and those made apparent from the foregoing description, are efficiently attained. Since certain changes may be made in the above construction without departing from the scope of the invention, it is intended that all matters contained in the foregoing description or shown in the accompanying drawings shall be interpreted as illustrative and not in a limiting sense.

It is also to be understood that the following claims are intended to cover all of the generic and specific features of the invention herein described, and all statements of the scope of the invention that, as a matter of language, might be said to fall therebetween.

What is claimed is:

1. A cord management device, comprising:
a substratum having a top surface and a bottom surface;
a receptacle attached to or integrated with the top surface
of the substratum on a first section of the substratum,

the receptacle having two or more apertures adapted to receive prongs extending from a plug end of an electrical cord, wherein the receptacle does not transfer electricity;

a first hook attached to or integrated with the top surface of the substratum on a second section of the substratum;

the first section of the substratum configured to separate from the second section of the substratum, and an adhesive on the bottom surface of the substratum, thereby allowing the first and second sections of the substratum to be secured to any object in need of the cord management device at any location on the object in need of the cord management device.

2. The cord management device of claim 1, wherein the first hook is outwardly facing with respect to the receptacle.

3. The cord management device of claim 1, wherein the receptacle is permanently secured to the top surface of the substratum.

4. The cord management device of claim 1, further including the first hook detachably connected to the receptacle.

5. A cord management device, comprising:
a substratum having a top surface and a bottom surface, wherein the top surface is attached to or integrated with a non-functional receptacle;

the receptacle having two or more apertures adapted to receive prongs extending from a plug end of an electrical cord, wherein the receptacle does not transfer electricity;

three or more hooks attached to or integrated with the top surface of the substratum in an equidistantly spaced, non-linear fashion; and

the bottom surface of the substratum configured to be attached to any object in need of the cord management device at any location on the object in need of the cord management device.

6. The cord management device of claim 5, further including an adhesive on the bottom surface of the substratum, thereby allowing the device to be secured to an object in need of a cord management device.

7. The cord management device of claim 5, further including a plurality of magnets on the bottom surface of the substratum, thereby allowing the device to be secured to an object in need of a cord management device.

8. The cord management device of claim 5, wherein one or more of the three hooks are outwardly facing with respect to the receptacle.

9. The cord management device of claim 5, wherein one or more of the three hooks are inwardly facing with respect to the receptacle.

10. The cord management device of claim 5, wherein the receptacle is secured between at least a first hook and a second hook.

11. The cord management device of claim 5, wherein the receptacle is permanently secured to the top surface of the substratum.

12. A cord management device, comprising:
a substratum having a top surface and a bottom surface, the bottom surface configured to be attached to any object in need of the cord management device at any location on the object in need of the cord management device;

a receptacle attached to or integrated with the top surface of the substratum on a first section of the substratum, wherein the receptacle includes two or more apertures

adapted to receive prongs extending from a plug end of an electrical cord and is non-functional;
a hook attached to or integrated with the top surface of the substratum on a second section of the substratum, wherein the first hook is detachably connected to the 5 receptacle; and
the first section of the substratum configured to separate from the second section of the substratum.
